NASAL SYRINGE

Application filed December 9, 1927. Serial No. 238,810.

Our present invention relates generally to syringes, and has particular reference to a syringe nozzle designed for application to the nostrils.

5 The proper and regular cleaning of the nasal passages, though generally neglected, is as a matter of fact perhaps second in importance only to the regular cleaning of the oral cavity and the teeth. The almost universal indifference toward a regular procedure of this character may be due to various factors.

A syringe or douche of the ordinary character wherein a nozzle has a single passage therethrough is extremely unsatisfactory and annoying in use. If the nozzle is applied to a nostril and the head thrown back to permit a small head of water to flow by gravity into the nasal passage, the stream embodies extremely little kinetic energy and is accordingly very unthorough in its cleansing effect. Moreover, if one or the other nasal passage is obstructed, the liquid will either stop flowing, or it will leak out past the nozzle and be 25 the cause of much annoyance without having accomplished any substantial alleviation of the obstruction.

If kinetic energy is imparted to a stream of the foregoing character, there is extreme danger of building up a hydraulic pressure within the nasal cavity, particularly if the passages are obstructed. The advantageous effects of kinetic energy are in this way counteracted and accompanied by the very disadvantageous effects of the hydraulic pressure into which the kinetic energy has been converted. The possibility of such a pressure causing injury is extremely great, particularly in view of the communication between the nasal cavities and the ears and also in view of the fact that the liquid and other matter within the nasal cavity is of a character which should be driven out rather than further in.

It is an important object of our present invention to provide a syringe which is of such simple construction and operation as to be usable with great facility at regular daily intervals; to provide a device which permits liquid to be forced with considerable kinetic 50 energy into the nasal passages without any

possibility of building up hydraulic pressure therein; and to provide a device which is so constructed and which operates in such a manner that its employment is unaccompanied by any of the annoyances or dangers exemplified above.

One feature of our invention lies in providing a syringe nozzle having concentrically arranged conduits, the inner one being adapted to guide a forced stream of liquid into the nasal passages, the outer one being adapted to fit snugly into a nostril so as to prevent haphazard spilling or leaking of the liquid, and the outer one serving further as a means for maintaining the interior of the nasal cavity under atmospheric pressure.

More particularly, our invention provides a construction wherein an annular space is provided between inner and outer concentrically arranged conduits; wherein this space communicates at one end with the atmosphere and terminates at its other end adjacent to the end of the inner conduit; and wherein this space serves as a predetermined passage for the outflowing stream.

It is an important object of our invention to provide a device which is extremely simple in construction, thereby rendering it inexpensive from a manufacturing standpoint and hence feasibly available for general use. In one embodiment of our invention the nozzle is formed of a single integral element which is so constructed and arranged as to be capable of manufacture in large quantities and at small cost by means of a turret lathe or the like. In another embodiment, the attenuated end of an ordinary rubber bulb may be itself adopted as the inner conduit, and the invention is carried out by the removable application thereto of a small integral stamping of extreme lightness and simplicity.

In a preferred embodiment, the device is formed of two elements, one of which comprises an ordinary strip of hard rubber tubing or the like, and the other of which comprises an integral solid member which may be molded or similarly manufactured with great ease and at small expense. The last mentioned member is provided with suitable bores, and the tubular element has its periphery

suitably shaped, so that the mere removable association of these two complementary elements will provide a neat, compact, and efficient device of the present character.

5 For the attainment of the foregoing objects and such other objects as may herein-after appear or be pointed out, we have constructed numerous devices embodying our invention and illustrated on the accompanying drawings in which—

10 Figure 1 is a side elevation of a nozzle constructed in accordance with our invention and shown attached to a rubber tube or the like;

15 Figure 2 is a longitudinal cross-section upon an enlarged scale taken substantially along the line 2—2 of Figure 1;

Figure 3 is an end view of the device shown in Figure 1;

20 Figure 4 is a longitudinal cross-section through a modified type of nozzle;

Figure 5 is an end view of the nozzle shown in Figure 4;

25 Figure 6 is a side view of a further modification, the nozzle portion being shown in cross-section; and

Figure 7 is an end view of the nozzle shown in Figure 6.

In Figures 1, 2, and 3, 10 represents a tube of rubber or the like which may lead from a 30 suitable bulb or similar source of pressure. The nozzle illustrated in these figures is constructed of two parts, the inner conduit element 11 and the outer conduit element 12.

35 The element 11 is a short tubular element which may be made of hard rubber or similar material. Its outer periphery is stepped as shown in Figure 2 to provide a main portion 13, a portion 14 of slightly reduced outside diameter, and an end portion 15 of further reduced outside diameter. The bore 16 may be of uniform diameter throughout.

40 The complementary conduit element 12 is formed of an integral molding or the like, such as bakelite, hard rubber, or similar material, and is substantially oval in shape. It is provided with a longitudinal bore 17 which is of uniform diameter and substantially equal to the outside diameter of the portion 14 of the element 11. The steps upon the 45 element 11 are so constructed and sized, and the complementary element 12 is of such a length that the portion 14 may be snugly and frictionally fitted into one end of the bore 17 as shown in Figure 2, while the extreme 50 end portion of the element 11 will project slightly from the opposite end of the bore 17. An annular space 18 is thereby provided around the attenuated end portion 15 of the element 11.

55 The nozzle element 12 is provided with an additional bore 19 extending at an angle to the main bore 17 and terminating immediately in front of the portion 14 when the two nozzle elements are associated with each other.

60 When the device is employed, the syringe

70 nozzle is inserted into a nostril, the element 12 being rounded and shaped so as to fit snugly. The size of the element 12 is such that the application thereof to a nostril will position only the extreme ends of both conduits within the nostril. The space 18 and the bore 19 will obviously afford a free communication between the interior of the nostril and the outside atmosphere, and in this way the interior of the nostril is maintained under atmospheric pressure. Liquid, such as salt water or the like, may now be forced with considerable force through the inner conduit element 11, and this liquid will emerge from the end of the element 11 in the form of a relatively narrow stream. By virtue of the 75 constantly maintained atmospheric pressure, this stream may be made to embody considerable kinetic energy without the danger of having this energy transformed into pressure energy. If the nasal passage is obstructed, the force of the stream will serve to wear down and break through the obstruction, just like a stream of water from a hose might wear down a bank of earth against which it is 80 played. The liquid poured into the nasal passages in this manner will find its way out either through the other nostril, if there be no obstruction, or through the predetermined return path provided by the passage 85 18 and the bore 19. This returning fluid will thereby emerge from the bore 19 in the form of a continuous stream, and since the device 90 is designed to be employed with the outer opening of the bore 19 directed downwardly, this stream of outflowing liquid may be directed in a sanitary and unannoying manner into a basin or the like. Where desired, an auxiliary flexible conduit may be frictionally attached to the outer end of the bore 95 19, as by means of a collar or the like, so as to 100 further guide the outflowing stream of the desired direction.

105 It will be obvious that the device illustrated in the foregoing figures is of extremely simple construction. The element 11 may be formed of a strip of hard rubber tubing, the stepped portions thereof being provided upon a lathe or the like. The complementary element 12 may be manufactured in a single molding operation. Furthermore, it will be noted that the association of the elements 11 and 12 is a separable one, thereby facilitating the cleaning thereof. In the form illustrated, 110 all the bores are of uniform diameter, and in this way there is a total absence of any shoulders or any recesses which would be difficult to maintain in a clean and sanitary condition.

115 In Figures 4 and 5, we have shown an embodiment of the invention which may be 120 constructed of a single integral element and which lends itself to expeditious manufacture upon a turret lathe or the like. The nozzle illustrated in these figures may be advantageously constructed of nickel or similar 125 130

metal, and comprises a tube portion 20 constituting the inner conduit element, and a skirt portion 21 constituting the outer conduit element. The skirt portion 21 extends integrally from the forward end of the tube 20 and flares rearwardly in the manner shown. A series of openings 22 are provided through the forward portion of the skirt 21, these openings having their axes substantially parallel to the device as a whole, and encircling the outer end portion of the tube 20. From another aspect, the integral portions 23 provided between the openings 22 constitute connecting portions which unite the inner and outer conduits and which keep these conduits in concentric relationship. The rear end of the tubular element 20 may be associated with a rubber tubing or the like as in the previously described embodiment.

The employment of this device will be understood from what has gone before. The space 24 within the skirt 21 maintains communication, through the openings 22, between the outside atmosphere and the interior of the nasal passages. This space serves also as a predetermined path for the outflowing liquid. The flare prevents formation of any air pockets and renders the outflow of the liquid efficient, uniform, and noiseless.

In Figures 6 and 7, we have illustrated a construction which is even simpler than the previous constructions, the nozzle being constituted of the forward tapered portion 25 of a bulb 26, together with the removably applicable cap or thimble 27. The latter may be produced by a simple stamping operation of relatively thin nickel or similar metal. It is shaped substantially like the skirt portion 21 of the previous embodiment, but the inner ends of the connecting portions 23 are joined together and bent rearwardly to constitute a bearing for the frictional accommodation of the tapered end 25. This bearing is denoted by the reference numeral 28, the openings by the reference numeral 29, and the connecting portions between these openings by the reference numeral 30.

The portion 25 is preferably tapered for the reason that bulbs of this character are readily available on the market, and for the additional reason that the provision of a predetermined sized bearing 28 will provide for uniformly positioning the device upon the end of the conduit 25 in the proper manner. The preferred manner of association is shown in the drawings, and it will be noted that the extreme end 31 of the portion 25 projects slightly ahead of the openings 29. This prevents any possible deflection of the stream passing through the portion 25 and entering the nasal passages.

In the last mentioned embodiment, the chamber or space 32 provided beneath the skirt and around the tapered portion 25

serves to maintain atmospheric pressure within the nostril and serves also as a guide for the outflowing liquid.

It will thus be seen that we have provided a device which is extremely simple not only from the standpoint of manufacture, but also from the standpoint of use. No complicated apparatus is required, and there can be no possibility of any misuse of the device. The latter is simple in nature, neat in appearance, and compact, thereby rendering it usable for frequent and regular use. Its compactness, cheapness, neatness of appearance, and possibility of cleaning, cooperate to provide an efficient and valuable bathroom accessory.

It will be obvious that changes in the details herein described and illustrated for the purpose of explaining the nature of our invention may be made by those skilled in the art without departing from the spirit and scope of the invention as expressed in the appended claims. It is therefore intended that these details be interpreted as illustrative and not in a limiting sense.

Having thus described our invention and illustrated its use, what we claim as new and desire to secure by Letters Patent is—

1. A nasal syringe comprising concentrically arranged inner and outer conduits, the inner one comprising a tubular element and the outer one comprising a bored element adapted to engage the inner one in said bore, the forward end of the tubular element projecting slightly beyond the forward end of the bored element, the latter having an additional bore communicating at an angle with the rear position of the annular space around the inner element, and means for forcing a stream of liquid with considerable kinetic energy through the inner conduit and out of said forward end.

2. In a nasal syringe, a two-piece nozzle comprising concentrically arranged inner and outer conduits, the inner one comprising an integral tubular element, the outer one comprising an element having a bore of uniform diameter and adapted to engage the inner one in said bore, and the periphery of the inner element being stepped so that one portion of said periphery fits snugly into one portion of said bore while an annular space is provided about another portion of said periphery.

3. In a nasal syringe, a nozzle comprising concentrically arranged inner and outer conduits, the outer one comprising an element having a bore of substantially uniform diameter, the inner one comprising a tubular element engageable in said bore, said tubular element having a main portion of diameter slightly greater than that of said bore, an adjacent portion of diameter substantially equal to that of said bore, and an end portion of diameter slightly less than that of said bore, whereby the outer element may snugly engage about said adjacent portion and in abutment

with said main portion and thereby provide an annular space about said end portion.

4. In a nasal syringe, a nozzle comprising concentrically arranged inner and outer conduits, the outer one comprising an element having a bore of substantially uniform diameter, the inner one comprising a tubular element engageable in said bore, said tubular element having an end portion of diameter 10 slightly less than that of the bore and an adjacent portion of diameter substantially equal to that of the bore, whereby the outer element may snugly engage about said adjacent portion and thereby provide an annular space 15 about said end portion, and said outer element having a second bore communicating with said annular space and terminating immediately in front of said adjacent portion.

5. As an article of manufacture, a nozzle 20 element comprising a solid substantially oval member having a longitudinal bore of uniform diameter throughout and having an auxiliary bore communicating with a midportion of the first named bore, said auxiliary bore extending from said midportion toward the thicker end of said oval member.

6. In a nasal syringe, a nozzle comprising frictionally engageable inner and outer conduit elements shaped to provide an annular 30 space between them, and means for separably associating said elements with one another upon repeated occasions into the same predetermined positional relationship wherein the inner element projects by a predetermined amount beyond the front end of the 35 outer element.

7. In a nasal syringe, a nozzle comprising frictionally engageable inner and outer conduit elements shaped to provide an annular 40 space between them, and means for separably associating said elements with one another upon repeated occasions into the same predetermined positional relationship wherein the inner element projects by a predetermined 45 amount beyond the front end of the outer element, said means comprising complementary abuttable shoulders on said elements respectively.

8. In a nasal syringe, a nozzle comprising 50 frictionally engageable inner and outer conduit elements shaped to provide an annular space between them, and means for separably associating said elements with one another upon repeated occasions into the same predetermined positional relationship wherein the inner element projects by a predetermined amount beyond the front end of the outer element, said means comprising an integral shoulder upon the inner element and an abutment surface on the outer element adapted to 60 encounter said shoulder.

9. In a nasal syringe, a nozzle comprising frictionally engageable inner and outer conduit elements shaped to provide an annular 65 space between them, and means for separably

associating said elements with one another upon repeated occasions into the same predetermined positional relationship wherein the inner element projects by a predetermined amount beyond the front end of the outer element, said means comprising an integral shoulder upon the inner element, and said outer element having an oval shape whereby the rear portion thereof constitutes an abutment adapted to encounter said shoulder.

10. A nasal syringe comprising a tubular conduit with an attenuated forward end, a substantially oval applicator member having a longitudinal bore of uniform diameter throughout and adapted to fit snugly over the forward portion of said tubular conduit so that the forward end of the latter projects slightly beyond the forward end of the oval member, an annular space being thereby provided around said forward end, said oval member having an auxiliary bore extending from said annular space diagonally rearwardly to establish communication between said annular space and the atmosphere, a squeezable bulb adapted to contain a liquid, and a conduit element connecting the outlet end of said bulb with the rear end of said tubular conduit; whereby said oval member may be applied to a nostril, whereby squeezing of the bulb will force a stream of liquid with considerable kinetic energy through the tubular conduit and out of its forward end, and whereby said annular space and auxiliary bore will prevent the development of liquid pressure within the nostril.

In witness whereof, we have signed this specification this 7th day of December, 1927.
